UNITED STATES PATENT OFFICE.

THOMAS G. HOWLAND, OF KILKENNY, MINNESOTA.

GAME-COUNTER.

SPECIFICATION forming part of Letters Patent No. 618,099, dated January 24, 1899.

Application filed April 5, 1898. Serial No. 676,586. (No model.)

To all whom it may concern:

Be it known that I, THOMAS G. HOWLAND, a citizen of the United States, residing at Kilkenny, in the county of Le Sueur and State 5 of Minnesota, have invented certain new and useful Improvements in Tallies; and I do hereby declare the following to be a full, clear, and exact description of the invention, such as will enable others skilled in the art to which 10 it appertains to make and use the same.

My invention has for its object to provide an extremely simple and efficient tally of very small cost; and to this end it consists of the novel devices and combinations of devices 15 hereinafter described, and defined in the claims.

The preferred form of my improved tally is illustrated in the accompanying drawing, wherein like numerals indicate like parts.

20 The figure of the drawing is a perspective view of the tally.

The body of the tally is in the form of a skeleton-like segment 1, with vertically-extended segmental flange 2 and with a hub portion 3, from the central portion of which the arc 25 of the segmental flange 2 is struck. The flange 2 is divided into three sections, which extend from or between the raised lugs 2^a, and each section is provided with notches 2^b or other 30 suitable subdivisions, which correspond to and represent the different digit-figures—to wit, "0" to "9," inclusive. The digit-figures are preferably marked on the horizontally-extended flange portion 1^a of the segment 1, opposite to the different notches which 35 stand therefor. If desired, lines or marks 1^b may be placed on the said flange portion 1^a to more clearly indicate the subdivisions thereof, and the subdivisions may be marked 40 "Units," "Tens," "Hundreds," &c., to clearly indicate the different decimal-orders for which 45 they stand.

The portion of the hub 3 which is opposite to the flange 2 is provided with a vertical 50 segmental flange 4, the upper edge of which is provided with three bearing-surfaces 4^a, that stand at three different levels. Three pointers or indicator-arms 5 are pivoted to the center of the hub 3, as shown, by means 55 of a screw 6. These arms 5 are of light spring metal or other suitable material and are pro-

vided at their long ends with downturned lips 5^a, which engage with notches 2^b to hold said arms or pointers wherever set. The short ends of these arms 5 work one on each of the 55 bearing-surfaces 4^a, so that the movement of no one of said arms will interfere with the movement of the other. As is obvious, these arms or pointers 5 coöperate one with each of the units, tens, and hundreds divisions or sections of the flange 2, and to make their functions more clear they may be marked the one "Units," the other "Tens," and the other "Hundreds," as illustrated. The raised lugs 2^a will limit the possible movements of said 65 arms or pointers to their operative zones of movement and will keep their short ends always in engagement with their coöperating bearing-surfaces 4^a. It is of course evident that the arms or pointers may be very readily 70 moved from one position to the other simply by springing them and that when they are set in engagement with any particular notch no amount of rattling or ordinary knocking about can possibly change their positions. 75

To adapt the device to be used on a commercial article or on a vessel containing such an article—such, for example, as a milk-can—I provide the hub portion 3 with a projecting loop 7, to which a buckled strap 8 is secured. 80

The many uses to which this device may be put may be amply illustrated by considering its use in connection with milk-cans. For example, suppose this device to be applied to large milk-cans and secured thereto as a permanent tag or check. Suppose also that these cans are collected in large numbers and taken to the creamery and the milk there sold, the cans of course being returned. Now by means of my improved tally it will be a very 85 simple matter after the milk has been weighed or measured, as the case may be, to set the pointers to indicate the amount of milk which the can contained, either in pounds or in liquid measure. It is the common practice at 90 present to weigh the milk at creameries, and hence, as the weight in pounds will run up into very high figures, it is important to have a tally that may be readily set to indicate all possible weights and which when set will keep 95 an accurate record of the amount recorded until after the can has been returned to the 100

owner. This much I have certainly accomplished with a device of extremely small cost and which may be manipulated by any one capable of reading figures.

5 It is of course evident that, if desired, the name of the owner of the can to which it is applied may be marked on the segment 1 or other part of the tally. It is also evident that alterations in the specific details of construction above described may be made within the scope of my invention.

10 It will be understood, of course, that the tally instead of being marked on a decimal scale might be marked with notations indicating other denominations—such, for example, as pints, quarts, pecks, &c., or ounces, pounds, &c.

15 What I claim, and desire to secure by Letters Patent of the United States, is as follows:

- 20 1. A tally consisting of a segmental body having the consecutively and continuously located sections appropriated to different denominations, and having said sections marked or subdivided to indicate the notations of the different denominations, in combination with a plurality of arms or pointers mounted on a common pivot at the focus of the arc of said segment and coöperating one with each of the sections thereof, substantially as described.
- 25 2. A tally, consisting of a segment divided into sections and marked to indicate the digits or notations of the different sections, and the plurality of independently-movable spring pointers or arms mounted on a common pivot at the focus of the arc of said segment

30 and coöperating one with each of the sections thereof, substantially as described.

3. In a tally, the combination with a segment divided into sections and marked to indicate the digits or notations of the different sections, and provided at its hub portion with a bearing-flange with bearing-surfaces at different heights, of pointers or arms mounted on a common pivot on said hub, engaging one with each of the bearing-surfaces of said flange and coöperating one with each section of said segment, substantially as described.

4. In a tally, the combination with the segment 1 divided into sections by the lugs 2^a indicating units, tens, hundreds, &c., and 50 notched as at 2^b to indicate the digits, of the plurality of independently-movable spring-arms 5 pivoted at 6 and provided with the lips 5^a for engagement with said notches 2^b, substantially as described.

5. In a tally, the combination with the segment 1, 2, 3, provided with the notches 2^b, indicating the digits, and the raised lugs 2^a, indicating the sections, and the bearing-flange 4 with bearing-surfaces 4^a, of the spring-arms 60 5 pivoted at 6 and provided with the lips 5^a, said parts operating substantially as described.

55 In testimony whereof I affix my signature in presence of two witnesses.

THOMAS G. HOWLAND.

Witnesses:
